UNITED STATES PATENT OFFICE.

THADDEUS F. BAILY AND FRANK T. COPE, OF ALLIANCE, OHIO, ASSIGNEES TO THE
ELECTRIC FURNACE COMPANY, OF ALLIANCE, OHIO, A CORPORATION OF OHIO.

MELTING-FURNACE.

1,373,787.

Specification of Letters Patent. Patented Apr. 5, 1921.

Application filed February 16, 1920. Serial No. 359,090.

To all whom it may concern:

Be it known that we, THADDEUS F. BAILY and FRANK T. COPE, citizens of the United States, both residing at Alliance, in the 5 county of Stark and State of Ohio, have invented a new and useful Melting-Furnace, of which the following is a specification.

Our invention relates to melting furnaces and more particularly to a furnace especially adapted for melting brass and provided with means for preventing the usual 10 loss of a considerable percentage of the zinc from the brass during the melting process.

It is well known to those versed in the 15 metallurgy of non-ferrous metals that in melting brass in the usual form of melting furnace a considerable amount of the zinc from the brass is lost in the form of zinc vapor which may be deposited around the 20 furnace in the form of a fine powder.

This loss of zinc from the brass is probably due to the great difference between the melting points of zinc and brass. As is well known to those skilled in the art, brass 25 is an alloy of copper and zinc in which the proportions of the two metals vary for different uses. The majority of these alloys contain a very large percentage of copper, the melting point of which is 1929°. As 30 the melting point of zinc is only 779° while the melting point of brass is 1692°, a considerable amount of zinc in the alloy is vaporized during the melting of the brass.

In the ordinary melting furnace such as 35 is in general use for melting brass a considerable per cent. of this zinc vapor is lost escaping from the furnace and being deposited around the furnace in the form of a fine powder. This loss of zinc from the 40 brass represents not only a loss of a certain per cent. of the metal but also changes the proportions of the alloy since owing to the high temperature of vaporization of copper there is no loss of copper from the alloy 45 during the melting process.

The objects of the invention are to provide a furnace especially adapted for melting brass in which means are provided for preventing the loss of zinc from the brass 50 in the form of zinc vapor, during the process of melting; and to generally improve and simplify melting furnaces of this character.

These objects are attained by providing

one or more condensers in communication 55 with the heating chamber of the usual melting furnace, the zinc vapor from the heating chamber passing into these condensers where it is condensed into metallic zinc. When a condenser has become partly filled 60 with metallic zinc it is removed from the furnace and the zinc emptied therefrom, the zinc which is thus received into the condensers representing the usual loss of zinc from the brass which in practice varies 65 from four to in some cases as high as twenty per cent. of zinc in the alloy.

With these objects in view the invention consists in the novel construction and arrangement of parts, hereinafter described, 70 illustrated in the accompanying drawings, and particularly pointed out in the appended claims, it being understood that various changes in the form, proportions, size and minor details of construction may be 75 made within the scope of the appended claims, without departing from the spirit or sacrificing any of the advantages of the invention.

The invention thus set forth in general 80 terms is illustrated in the accompanying drawings forming part hereof, in which—

Figure 1 is a vertical sectional view through a brass melting furnace showing a 85 condenser in place upon the furnace.

Fig. 2 is an enlarged sectional view through a type of condenser which is well adapted for use with the furnace.

Fig. 3 is a fragmentary sectional view through a portion of a furnace showing a 90 modified form of condenser.

Similar numerals of reference indicate corresponding parts throughout the several figures of the drawings.

Although our invention may be applied 95 to any form of melting furnace we have illustrated it in the accompanying drawings in connection with an electrically heated brass melting furnace of the type upon which we obtained United States Letters 100 Patent No. 1,272,286, July 8, 1918.

In this form of furnace the numeral 1 indicates a metal plate upon which the base 2 of the furnace is supported, this base being composed of suitable insulating material such as bricks formed of kieselguhr, a metal plate 3 being preferably located upon said brick base and supporting the brick 105

work 4 preferably formed of fire brick and provided with the concave hearth 5 which is lined with suitable brick, heat resisting material and provided at one side with a 5 reduced neck 6 having a pouring spout 7. A circular wall 8 formed of fire brick or other suitable material is supported upon the brick work 4 and a roof 9 preferably concaved as shown is provided over said 10 circular wall, thus forming a heating chamber between the roof, hearth and circular walls.

Mounted within the heating chamber intermediate the hearth and roof thereof and 15 spaced from the circular side wall is a resistance trough 10 preferably circular as shown. This trough is provided with a resistance body consisting of a carbonaceous material in granular form, such as 20 crushed coke, graphite, carbon or the like, said resistance material being designated by the numeral 11. The trough is preferably formed of refractory material or the like and comprises the bottom wall 12 and the 25 circular upright walls 13, and is supported upon the radial supporting walls 14, composed of fire brick or other heat resisting material.

Embedded in the resistance material preferably at diametrically opposite sides of the 30 trough are suitable electrodes 28 which extend through the furnace walls in the usual manner. It is, of course, understood that these electrodes are arranged in an electric 35 circuit, such construction being well known in this art. When current is supplied to the electrodes it will be conducted from one electrode to the other through the resistance material, thus raising the resistance material 40 to an intense heat.

A metal casing 16 is preferably provided around the furnace and it will of course be understood that furnaces of this type can be mounted so that they may be tilted to 45 pour the melted metal therefrom and for this purpose any usual construction may be provided for rocking or tilting the furnace to pour the melted brass therefrom through the pouring spout 7, but this feature of the 50 furnace construction forms no part of the present construction and is therefore not illustrated, since it is well known and in general use.

The heat rays which radiate downward 55 from the resistance trough will strike directly upon the hearth containing the metal to be melted while those rays which radiate upward from the trough will strike the arched roof, the greater majority of said 60 rays being reflected through the central opening in the trough upon the metal on the hearth.

In melting brass in any melting furnace such as in general use, the low melting point 65 of zinc causes a certain amount of the zinc

in the brass to vaporize during the melting of the brass, this zinc vapor escaping from the furnace.

In order to overcome this loss we provide one or more suitable apertures 17 in the upper portion of the heating chamber, a condenser 18, provided with the reduced neck 19 being fitted into each aperture. Each of these condensers is provided with the downwardly inclined condensing chamber 20, a 75 small aperture 21 being formed in the outer end of the condenser to cause a slight draft from the heating chamber through the condenser drawing the zinc vapor which is given off by the melting brass into the 80 condenser, the vapor contacting with the cooler walls of the condensing chamber and condensing, being deposited in the bottom of the condensing chamber in the form of metallic zinc. 85

Any suitable support for the condenser, such as the bracket 22 may be provided upon the furnace wall in order that the condensers may be held in place upon the furnace and easily removed therefrom when it 90 is desired to remove the condensed zinc therefrom. By the use of this condenser, the zinc which would ordinarily escape from the ordinary form of melting furnace in the form of zinc vapor is thus collected and 95 condensed within the condenser, thus producing a considerable saving of zinc.

In the modification shown in Fig. 3 the condenser 18^a is provided with a reduced neck 19^a at its upper end which fits into a 100 suitable aperture in the upper portion of the heating chamber, a downwardly and inwardly inclined neck 25 being provided at the lower end of the condenser, this neck passing through a suitable aperture 26 in 105 the heating chamber just above the hearth 5 of the furnace. With this construction the zinc as it is condensed within the condenser 18^a will be carried through the inclined neck 25 back to the hearth of the 110 furnace.

We claim:

1. A melting furnace and a condenser communicating with the heating chamber thereof. 115
2. A melting furnace provided with an aperture in the heating chamber thereof and a condenser located in said aperture and communicating with the heating chamber.
3. A melting furnace and a condenser 120 communicating with the heating chamber thereof and extending beyond the exterior of the furnace.
4. A melting furnace and a condenser 125 communicating with the heating chamber thereof, the condenser provided with a large condensing chamber.
5. A melting furnace and a condenser 130 communicating with the heating chamber thereof, the condenser provided with a large

condensing chamber having a reduced aperture at its outer extremity.

6. A brass melting furnace having a zinc vapor condenser communicating with the heating chamber of the furnace.

7. A brass melting furnace provided with an aperture communicating with the heating chamber thereof and a zinc vapor condenser having a reduced neck located in said aperture and communicating with the heating chamber.

8. A brass melting furnace and a zinc vapor condenser communicating with the heating chamber of the furnace and extending beyond the exterior of the furnace.

9. A brass melting furnace and a zinc vapor condenser provided with a reduced neck communicating with the heating chamber of the furnace and having an enlarged condensing chamber located beyond the exterior of the furnace.

10. A brass melting furnace and a zinc vapor condenser having a reduced neck com-

municating with the heating chamber of the furnace and having an enlarged downwardly inclined condensing chamber located beyond the exterior of the furnace.

11. A brass melting furnace having an aperture communicating with the heating chamber thereof and a zinc vapor condenser provided with a reduced neck located in said aperture and with an enlarged condensing chamber extending beyond the exterior of the furnace and provided with a reduced aperture at its outer extremity.

12. A brass melting furnace and a condenser communicating with the upper portion of the heating chamber thereof, the condenser provided with an inclined neck communicating with the heating chamber near the hearth of the furnace.

In testimony that we claim the above, we have hereunto subscribed our names.

THADDEUS F. BAILY.
FRANK T. COPE.
